Inventor:

Leroy M. Streeter

United States Patent Office.

LEROY M. STREETER, OF OSHKOSH, WISCONSIN.

Letters Patent No. 104,227, dated June 14, 1870.

IMPROVED CLOTHES-DRIER.

The Schedule referred to in these Letters Patent and making part of the same

To all whom it may concern:

Be it known that I, LEROY M. STREETER, of the city of Oshkosh, in the county of Winnebago and State of Wisconsin, have invented certain new and useful Improvements in Clothes-Racks; and I do hereby declare that the following is a full, clear, and exact description thereof, reference being had to the accompanying drawing and to the letters of reference marked thereon.

To enable others skilled in the art to construct and use the invention, I will proceed to describe it.

My invention consists in the combination and arrangement of parts of a clothes-rack, as will herein-after be more fully specified.

Figures 1, 2, 3, and 4, are elevations of the rack, with the arms variously adjusted.

Figure 5 is a perspective view.

Figure 6 is a vertical section.

Fig. 1 shows the position of the arms, suitable for attaching a clothes-line for ordinary use.

Fig. 2 shows the position of the arms when the hooks J J are to be used.

Fig. 3 shows the position of the arms suitable for use in drying and dressing ladies' skirts.

Fig. 4 shows the arms folded, in which position the apparatus may be used as an ordinary reel.

A A are the arms, attached by a pivot joint at the end H to the head-block D, and connected by the braces B B to the sliding block C, the braces being attached by a pivot joint to the arm at K, and to the sliding block at L.

F is the stay-block, connected to the head-block D by the stay-rods E, passing loosely through the sliding block C. The office of the stay-rods is to keep the head-block D and sliding block C in position relative to each other.

I is a shoulder on the shaft G upon which the head-block rests.

O is a pin through the shaft, above the head-block. The sliding block C is operated by means of a cord, b, and pulley a, and is held in any position by fastening the cord to the pin, the cord being attached to the sliding block, and the pulley and pin to the head-block.

J J are hooks for hanging articles on when the arms are raised, as in fig. 2.

Having thus described my invention, What I claim as new, and desire to secure by Letters Patent, is—

1. The combination of the vertical shaft G, stay-rods E, head-block D, stay-block F, sliding disk C, arms A, braces B, pulley a, and belt or cord b, constructed and arranged to operate substantially as described, for the purpose hereinbefore specified.

2. The stay-rods E, in combination with the head-block D, stay-block F, and sliding block C, constructed as specified, for the purpose stated.

LEROY M. STREETER.
